UNITED STATES PATENT OFFICE.

EUGENE R. CARICHOFF, OF SCHENECTADY, NEW YORK, ASSIGNOR TO GENERAL ELECTRIC COMPANY, A CORPORATION OF NEW YORK.

CONTROL OF ELECTRICALLY-OPERATED SWITCHES.

982,032.

Specification of Letters Patent.

Patented Jan. 17, 1911.

Application filed September 19, 1910. Serial No. 582,640.

To all whom it may concern:

Be it known that I, EUGENE R. CARICHOFF, a citizen of the United States, residing at Schenectady, in the county of Schenectady, 5 State of New York, have invented certain new and useful Improvements in Control of Electrically-Operated Switches, of which the following is a specification.

My invention relates to the control of 10 electrically operated switches and particularly to the control of a plurality of said switches or contactors intended for operation in succession. A plurality of successively operated contactors are often employed 15 in the control of electric motors and my invention is particularly adapted for use in this connection.

In one aspect, my invention may be considered as an improvement on such a system 20 of control as is typified in the patent to A. S. Cubitt, 941,108, November 30, 1909, commonly referred to as a "two-wire notching control" system. In systems of this 25 general type it may often happen that the notching relay mechanism is slower in operation than the contactors and that two or more contactors will close in rapid succession before the relay mechanism becomes effective to delay their operation in the 30 manner intended.

One of the objects of my present invention is to provide an arrangement in which the incorrect mode of operation above referred to will be positively prevented. 35 In carrying out my invention, I arrange a two-wire notching control system with enough resistance in the actuating circuits to prevent the contactors from operating until one of the switch members of the relay 40 mechanism has operated and closed certain contacts which cause the reduction of resistance in the actuating circuit. Since the notching relay mechanism is so arranged that these contacts are closed after the contacts in the other actuating circuit have been 45 opened, one contactor cannot close until the actuating circuit of the succeeding contactor has been interrupted at the relay mechanism. The closing of two contactors in rapid succession without being controlled by the relay mechanism is therefore 50 impossible.

My invention will be fully understood from the following description, taken in

connection with the accompanying drawing, 55 in which—

Figure 1 represents diagrammatically a simple control system embodying my invention; and Fig. 2 shows a modified arrangement which may be employed in the system 60 of Fig. 1.

Referring to the drawing, it will be seen that I have shown my system in connection with the starting of a series motor by cutting resistance out of the circuit thereof, but it is 65 obvious that my invention is not limited to the control of this particular type of motor, but may be applied to any type of motor either alternating or direct current.

In the drawing, A represents the armature and F the field of a series motor having resistances R, R' and R² connected in series therewith and adapted to be consecutively cut out of circuit to bring the motor to running speed. A series of contactors 1, 2, 3, 75 and 4 are arranged first to close the motor circuit through the resistance and then cut out the sections consecutively. The contactor 1 is provided with two interlocks 5 and 6 adapted to be closed when the contactor is closed and an interlock 7 adapted to be opened when the contactor closes. Contactors 2 and 3 are provided with similar interlocks 8, 9, 10 and 11, 12, 13, respectively, while the contactor 4 is provided with only 80 two interlocks 14 and 15, the former to be closed when the contactor closes, while the latter opens when the contactor is closed. A pair of relays 16 and 17 are arranged to be operated alternately to successively close 85 the contactors. Relay 16 comprises a winding co-operating with a core provided with a contact member 18 which is arranged to bridge the contacts 19 when the core is lifted, and to bridge the contacts 20 when 90 the core is down. Relay 17 is provided with a similar winding co-operating with a core having a contact member 21 adapted to operate between contacts 22 and 23. Each core 95 of the relay is likewise controlled by series 100 windings 24 and 25, respectively, which prevent the corresponding core from dropping when the current is excessive. A resistance r is arranged to be connected in shunt to the winding of the relay 16 when the contacts 19 105 are bridged and a similar resistance r' is adapted to be connected in shunt with the winding of relay 17 when the contacts 22

are bridged. A master controller C, having two positions, *a* and *b*, is arranged to control the relays and contactors.

The arrangement of circuits and mode of operation are as follows: To start the motor 5 the master controller C is moved to position *b*, whereupon the relay 16 and coil of contactor 1 will be energized, the circuit being as follows: from the line through the controller C, conductor 26, across contacts 23, 10 through winding of relay 16, conductor 27, interlock 7, winding of contactor 1 to ground. This energizes the winding of relay 16 sufficiently to lift its core and bridge contacts 19. The winding of the relay 16, however, is of 15 high resistance and contactor 1 will not close with this resistance in series with it. When the contacts 19 are bridged, however, a shunt circuit is established through the resistance r' , whereupon the contactor 1 will close and 20 complete the motor circuit through the resistance sections R , R' and R^2 . When contactor 1 closes, the actuating circuit is opened at interlock 7 and a holding circuit is closed at interlock 6 through the contact fingers *c* 25 and *d*. The closing of contactor 1 likewise closes interlock 5 which is in the circuit of contactor 2. The actuating circuit of contactor 1 being opened at interlock 7, relay 16 is deenergized and contacts 20 will be 30 again bridged, providing the current in the winding 24 is not excessive. This closes a circuit through relay 17 and winding of contactor 2, the circuit being as follows: from line through controller C, conductor 26, contacts 20, winding of relay 17, conductor 28, interlocks 5 and 10, and winding of contactor 2 to ground. Contactor 2 will not close, however, until the relay operates and 35 bridges contacts 22, thereby connecting the resistance r' in shunt with the winding of the relay 17. As soon as the relay 17 operates, contactor 2 closes and cuts out section of resistance R . Similarly the circuit of 40 relay 2 is opened at interlock 10 and a circuit is completed through the winding of contactor 3 at interlock 8. The relay 17 thereupon drops and relay 16 again operates to 45 close the contactor 3, by the closing of which the relay 16 is deenergized and the relay 17 energized to close the contactor 4.

It will be seen that no one of the contactors will operate until the relay which 50 controls it has completed its operation, so that by the time it has completed its operation the relay has deenergized the winding of the other relay so that it is impossible for one contactor to close until the actuating circuit of the succeeding contactor has been interrupted. It is therefore impossible to 55 close two contactors in rapid succession without the control of the relay mechanism. The operation of the contactors may be stopped at any time by moving the controller 60 to position *a*, since the operation of the 65

relays is interrupted by the movement of the contact finger *c* off of its corresponding segment.

In Fig. 2 I have shown a slightly modified form in which a single series relay 29 controls the notching relays, so that the windings 30 and 31 of the relays will not operate when the current is excessive. Instead of having the relay windings of high resistance, I employ the auxiliary resistances r^2 70 and r^3 which are to be connected in series with the windings 30 and 31 respectively when the relays are down and to be short circuited when the relays are up. The operation of parts will be substantially the 75 same as in Fig. 1. Conductors 27 and 28 are the actuating wires of the contactors and as each relay operates, it short circuits the resistance in series with the winding and thereby reduces the resistance of the actuating 80 circuit and allows the corresponding contactor to close. The operation of the notching relay is all the time under the control of the series winding and when the current becomes excessive it will stop the operation. 85

While I have described my invention as embodied in concrete mechanism and as operating in a specific manner, in accordance with the patent statutes, it should be understood that I do not limit my invention thereto, since various modifications thereof will suggest themselves to those skilled in the art without departing from the spirit of my invention, the scope of which is set forth in 90 the annexed claims.

What I claim as new, and desire to secure by Letters Patent of the United States, is,—

1. In combination, a plurality of contactors intended for operation in succession, two actuating circuits leading to alternate contactors, relay mechanism for energizing 105 said actuating circuits alternately, and connections whereby the resistance of the actuating circuits is alternately decreased upon the successive operation of the relay mechanism to cause said contactors to close successively.

2. In combination, a plurality of contactors intended for operation in succession, two actuating circuits leading to alternate contactors, relay mechanism arranged to be energized simultaneously with the alternate actuating circuits, and connections whereby the resistance of each actuating circuit is 110 decreased to close the respective contactor upon each operation of the relay mechanism.

3. In combination, a plurality of contactors intended for operation in succession, two actuating circuits leading to alternating contactors, relay mechanism arranged to be energized in series with the alternate actuating circuits, and connections whereby the 125 resistance of each actuating circuit is decreased to 130 close the respective contactor.

creased to close the respective contactor upon each operation of the relay mechanism.

4. In combination, a plurality of contactors intended for operation in succession, two actuating circuits leading to alternate contactors and a relay mechanism for energizing the said actuating circuits alternately comprising switches located in said actuating circuits, an actuating magnet for opening each of said switch contacts, a shunt circuit around each magnet coil, and contacts in said shunt circuit closed by the corresponding magnet when energized.

5. In combination, a plurality of contactors intended for operation in succession, two actuating circuits leading to alternate contactors, and a relay mechanism for energizing said actuating circuits alternately comprising switch contacts one located in each of said actuating circuits, an actuating magnet for opening the switch contacts of each circuit, each magnet having its coil controlled by the switch contacts of the other magnet, a shunt circuit around each magnet coil, and contacts in said shunt circuits closed by the corresponding magnet when energized.

6. In combination, a plurality of contactors intended for operation in succession, two actuating circuits leading to alternate contactors, switches closed by each contactor located in the actuating circuit of the succeeding contactor, and a relay mechanism for energizing said actuating circuits alternately comprising two actuating magnet coils having movable cores one located in each of said actuating circuits, a shunt circuit around each magnet coil, normally closed switch contacts located in each actuating circuit, normally open switch contacts located in said shunt circuits, and connections whereby each core in its movement in response to the energization of its coöperating magnet coil first opens the switch contacts in the other magnet coil and then closes the switch contacts located in the shunt circuit around the magnet coil coöperating with that core.

7. In combination, a plurality of contactors intended for operation in succession, two actuating circuits leading to alternate contactors, relay mechanism having an operating winding for each actuating circuit arranged to be alternately energized simultaneously with the energization of the alternate actuating circuits to operate the relay mechanism, and connections whereby the resistance of the alternating actuating circuits is decreased upon the closing of the relay mechanism to close the successive contactors.

8. In a relay mechanism, two actuating magnet coils each having movable cores coöperating therewith, switch contacts operated by each core connected with the actuating winding of the other core, a shunt circuit around each of said actuating windings and switch contacts operated by each core located in the shunt circuit coöperating with said core.

9. In a relay mechanism, two actuating magnet coils each having movable cores coöperating therewith, normally closed switch contacts opened by each of said cores in their movement in response to the energization of said actuating coil, each set of switch contacts being connected in circuit with the actuating coil operating the other contacts, a shunt circuit around each of said actuating coils, and switch contacts closed by each core located in the shunt circuit around the coil coöperating with that core.

In witness whereof, I have hereunto set my hand this 16th day of September, 1910.

EUGENE R. CARICHOFF.
